UNITED STATES PATENT OFFICE.

ERNEST A. WAGNER, OF GARDINER, MAINE.

FOOT COVERING.

Application filed June 2, 1920. Serial No. 386,016.

To all whom it may concern:

Be it known that I, ERNEST A. WAGNER, a citizen of the United States, residing at Gardiner, in the county of Kennebec and State of Maine, have invented certain new and useful Improvements in Foot Coverings, of which the following is a specification.

The invention relates to footwear and 10 more particularly to the class of baby shoes or bootees.

The primary object of the invention is to provide, in a manner as hereinafter set forth, a shoe of such class, having its body 15 portion formed from a flat piece of flexible material provided with a connecting extension and a pair of independently operable forming lacings for gathering the front and rear terminals of the flat piece of material 20 together to form a vamp and a back closed throughout, each of said lacings being independently adjustable to provide for a snug but comfortable fitting of the shoe to the foot of the wearer; as well as further providing a shoe having a neat and attractive 25 appearance when worn.

Another object of the invention is the provision of a shoe of this character, wherein the foot of the wearer can be readily inserted therein and removed therefrom, and when worn cannot be kicked off or lost from the foot.

A further object of the invention is the provision of a shoe of this character, wherein 35 in a tongue is mounted in the forepart thereof and is attached in a novel manner, so as to completely close the shoe at said forepart, irrespective of the adjustment of its toe end and particularly when the latter is properly 40 shaped on the adjustment thereof.

A still further object of the invention is the provision of a shoe of this character, wherein minimum labor is required in the making thereof, the shoe when completed 45 being neat and attractive in appearance, serviceable, comfortable when worn, and inexpensive to manufacture.

With these and other objects in view, the invention consists in the features thereof, 50 combination of elements and arrangement of parts as will be hereinafter fully described, illustrated in the accompanying

drawings, and pointed out in the claims appended hereto.

In the accompanying drawing:

Figure 1 is a perspective view of a shoe constructed in accordance with the invention.

Figure 2 is a rear elevation thereof.

Figure 3 is a plan view of the blank from 60 which the shoe is made.

Figure 4 is a top plan view with the upper of the shoe open showing in detail the toe and heel portions.

Figure 5 is a sectional view on the line 65 5—5 of Figure 4.

Similar reference characters indicate corresponding parts throughout the several views in the drawing.

Referring to the drawing in detail:

A shoe, in accordance with this invention, comprises a body portion 5, formed from a flat piece of flexible material, preferably leather, to provide when the shoe is set up, a continuous sole and heel portion 6, 7, respectively, a gathered vamp 8, extending rearwardly from the toe portion, an upper 9, having the rear thereof gathered to form an adjustable back 10 including a vertical tongue 15, which closes the back throughout. The forward terminal of the flat body 5, is provided with a series of eyelets 19, and the rear terminal portion of said flat body 5, is formed with a series of eyelets 12. Carried by the forward terminal of the flat 85 body 5, and extending through the eyelets 19, is a primary forming lacing 20, and extended through the eyelets 12 is a secondary forming lacing 13. The lacings 20 and 13 are independent of each other and the former is employed to set up when the terminals thereof are secured together, the gathered vamp 8. The lacing 13, is employed when its terminals are connected together as at 14, to provide the gathered back 10 and 95 the latter is arranged inwardly with respect to said secondary lacing. The primary and secondary lacings 20 and 13 permit of independently adjusting the vamp 8 or back 10 when occasion requires.

The upper 9 at the forepart is open and adjacent to one edge thereof are carried buttons 16, while the opposite edge has fastened thereto a closure flap 17, provided

with suitable buttonholes 18 for the engagement of the buttons 16 therein to fasten the said flap 17 in closed position.

The vamp extension 8 contiguous to its free edge is formed with the series of holes or eyelets 19, through which is trained the primary forming lacing 20, so that said vamp extension can be adjusted and shaped about the toe end of the shoe so as to permit the said toe end to conform to the foot of the wearer the lacing 20 being adjusted for this purpose and upon drawing upon the same, the vamp extension 8 is formed to the desired comfort of the wearer about the toe portion of the foot.

Arranged to be carried by the primary lacing 20 interiorly of the shoe is a front tongue 21, the same being provided with suitable holes or eyelets 22 to receive the lacing 20, which is trained through said holes or eyelets and in this manner the tongue 21 will be carried in the shoe to completely close the forepart thereof between the adjustable vamp extension 8 and the front closure flap 17.

The interior of the shoe may be constructed with a lining, while the continuous sole and heel 6 and 7 may have adapted thereto a separate outer sole and heel. The edges of the vamp extension 8 and the upper 9 may be reinforced through the medium of a suitable binding or said edge cut to ornament the same. If found desirable an inner sole may be arranged within the shoe.

It will be clearly apparent that the shoe can be adjusted by the lacings 13 and 20 at both the heel and forepart so that the shoe can be snugly fitted upon the foot of the wearer to assure comfort and thereby enabling the shoe to be fitted to various sizes of feet.

The shoe sole 6, heel 7, vamp extension 8 and upper 9 with the adjustable back 10, is made from the blank 23, and by the loosening of the lacings 13 and 20, at the heel and forepart of said shoe the same can be brought to a substantially flattened condition, it being readily obvious that the shoe can be easily applied to and removed from the foot of the wearer and on the fastening of the shoe upon the latter, it cannot be kicked off or lost.

From the foregoing, it is thought that the construction of the baby shoe or bootee will be clearly understood and that the ad-

vantages thereof will be obvious, therefore, a more extended explanation has been omitted.

What is claimed is:

1. A shoe of the class described comprising a flat piece of flexible material having its forward terminal portion formed with a series of eyelets, a primary lacing extended through said eyelets and having its ends secured together thereby forming the forward terminal portion of said piece into a gathered vamp extending over and projecting rearwardly from the toes of the wearer, said piece having the rear terminal portion thereof provided at opposite sides with eyelets, and a secondary lacing independent of the primary lacing and extending through said rear eyelets and having its ends secured together thereby forming the rear terminal portions of said piece into a vertically disposed gathered integral back including a vertical tongue, said tongue closing throughout said back, the latter being arranged inwardly of the secondary lacing.

2. A shoe of the class described comprising a flat piece of flexible material having its forward terminal portion formed with a series of eyelets, a primary lacing extended through said eyelets and having its end secured together thereby forming the forward terminal portion of said piece into a gathered vamp extending over and projecting rearwardly from the toes of the wearer, said piece having the rear terminal portion thereof provided at opposite sides with eyelets, a secondary lacing independent of the primary lacing and extending through said rear eyelets and having its ends secured together thereby forming the rear terminal portions of said piece into a vertically disposed gathered integral back including a vertical tongue, said tongue closing throughout said back, the latter being arranged inwardly of the secondary lacing, an extension carried by one side of said piece and positioned rearwardly with respect to said front eyelets and projecting over the instep of the wearer and having means independent of either lacing for connecting it to the other side of said piece rearwardly of the front eyelets to secure the shoe on and around the ankle of the wearer.

In testimony whereof, I affix my signature hereto.

ERNEST A. WAGNER
